RECOVERY OF OIL FROM TAR SANDS

Malden C. Lowman, Jr., San Rafael, and Edwin J. Fisch, Castro Valley, Calif., assignors to Shell Development Company, New York, N. Y., a corporation of Delaware

Application May 24, 1957, Serial No. 661,501

5 Claims. (Cl. 208—11)

This invention relates to an improved process for extracting crude oil from bituminous sand, with the crude oil being separated in a deasphalted component and an asphaltene component.

There are several large occurrences of bituminous sand in the world and much effort has been exerted to the development of methods by which the bitumen or crude oil may be separated from the sand and made available for use. The term bituminous sands is used herein to include those materials commonly referred to as oil sands, tar sands, and other like oil bearing materials. Various schemes have been proposed and tried with varying degrees of success. It is common practice to separate the crude oil or bitumen from the sand as a single component which separated bitumen may then be coked to produce a coker distillate which can be further refined in accordance with conventional refinery practices. In an alternative, the raw sand may be directly retorted in either a moving or a fluid bed system to produce a coker distillate with the coke which deposits on the sand being burned to provide the process heat.

Both of these general approaches have a common inherent disadvantage in that during coking the distillate is cracked. Cracking, while necessary for obtaining economic yields, results in some degradation of the distillate quality. Of course, in the first approach mentioned above it would be possible to solvent extract the recovered bitumen to obtain a deasphalted component and thereby avoid the cracking of this valuable component in its separation from the rest of the bitumen but to do so would require an additional and expensive operation over and above that required for the separation of the crude oil from the mineral matter. We have found that it is possible to operate the sand-crude oil separation procedure in a manner to provide simultaneously a deasphalted component and an asphaltene fraction, without the necessity of employing a second step, apart from the separation procedure itself, and without resorting to a thermal cracking operation.

It is an object of this invention to provide an improved procedure for the separation of crude oil from bituminous sand. It is a further object of this invention to furnish a process in which the crude oil is separated from the sand in a deasphalted component and an asphaltene component.

These and other objects will become more apparent with a study of the description of the invention taken in conjunction with the accompanying drawing which is a diagrammatic representation of a preferred system for performing the improved process.

It has now been discovered that the crude oil associated with a bituminous sand may be advantageously and efficiently separated from the sand in a process which will simultaneously fractionate the crude oil, making immediately available a deasphalted oil which can then be further refined by more or less typical refinery procedures. The sand from the process is substantially

2

oil free. Generally speaking, it is contemplated to supply an aqueous pulp of the bituminous sand to a vertical extraction zone and to flow a liquid low molecular weight paraffinic solvent in an upward direction of the vertical extraction zone in countercurrent direction to the downwardly descending sand. During the countercurrent movement of the aqueous pulp and solvent, there is formed a deasphalted oil and solvent phase, an asphaltene phase diluted with a lesser portion of the solvent, a water phase and a substantially oil-free sand. The several phases and sand are then separated into distinct layers with the asphaltene-enriched layer being disposed below the point of introduction of the hydrocarbon solvent and the water layer immediately below the asphaltene layer. The sand settles to the bottom of the water layer. A deasphalted-oil enriched solvent layer forms above the point of introduction of the aqueous pulp.

There are several inherent advantages in the improved process which makes possible its practice. It is essential that the sand be initially thoroughly water wet to forestall subsequent oil wetting of the sand surfaces during the solvent extraction. The control of the pH to the alkaline side is frequently desirable to obtain a clear separation. The water layer which forms at the bottom of the extraction zone serves a very useful purpose in that it assures deentraining of any hydrocarbon material that may possibly be associated with the falling sand. As will be subsequently described, regulation of the depth of the water layer facilitates the removal of the overlying asphaltene-enriched layer.

Various low molecular weight paraffinic hydrocarbons may be used as a solvent. It is best that the solvent contain no appreciable amount of hydrocarbons having more than six carbon atoms per molecule. Among the desirable solvents are propane, butane, mixtures of propane and butane and light ends collected in the further processing of the separated crude oil. Where the site of the bituminous deposit is geographically isolated, the light ends may be conveniently and advantageously used. The solvent is continually recovered and recirculated to the extraction zone. The extraction zone is closed and will have a pressure dependent upon the vapor pressure of the hydrocarbon solvent at the temperature of the operation. For instance, where propane is being employed and the process is conducted at a temperature in the vicinity of 100° F., the pressure will be approximately 175 p. s. i. g. This high pressure points up an advantage in using light hydrocarbon ends which will usually have a vapor pressure of perhaps 25 pounds p. s. i. g. at the same temperature.

The pulper employed may be any of the type conventionally used in the preparation of crude bituminous sands for extraction. Preferably the water which is added to the bituminous sand contained in the pulper is heated to a temperature in the range of 100–200° F. as an elevated temperature lowers the viscosity of the crude oil making it more easily separated from the sand. The water may be introduced warm to the pulper or alternatively steam may be introduced with the water or directly into the pulper. The primary purpose of the pulping operation is to disrupt the oil structure or film and thereby disperse the crude oil throughout the pulp as detached flecks among water wet sand grains. This places the crude oil in a form which makes it possible to solvent extract it readily in the subsequent extraction step. The amount of water added to the bituminous sand will vary considerably depending among other things upon the initial water content of the sand and the amount of clay present. Clay tends to create an emulsion and

in some instances, it may be necessary to use larger quantities of water to break the emulsion.

The hydrocarbon solvent is introduced to the extraction zone at a temperature in the vicinity of 70° F. or thereabouts depending on the temperature of the cooling water available. The amount of solvent used varies greatly but it is generally contemplated that six to two parts of the hydrocarbon solvent per one part of the crude oil in the bituminous sand will provide satisfactory extraction. The outlet temperature of the hydrocarbon solvent in solution with the deasphalted oil will depend on its inlet temperature and the temperature of the aqueous pulp entering the extraction zone. But in any event, since relatively large quantities of solvent are employed, the exit temperature will not be greatly in excess of the temperature of the incoming stream of solvent. It is believed that the solvent functions to separate and coalesce the crude oil flecks into two phases, viz. the asphaltene enriched phase and the deasphalted-oil enriched extract. It can be generally expected that the asphaltene-enriched phase will have a specific gravity in the vicinity of .9 and the deasphalted oil enriched phase a specific gravity of approximately from .6 to .8. The amount of solvent in the overhead deasphalted oil layer is much greater than that diluting the asphaltenes.

It has been occasionally experienced in the deasphaltizing of hydrocarbon oils that the precipitated asphaltenes plug the fractionating tower. This plugging has normally occurred in the region adjacent and below the feed entry. Various schemes have been suggested for preventing the plugging and among these is the use of very finely divided solid particles. It may be that the fortuitous presence of the fine pulp sand forestalls the occurrence of this phenomenon in our process. In any event, it is believed that the cascading sand passing over the baffles of the extraction zone afford an erosion effect which keeps these baffles clean.

The retention time in the pulper need be only long enough to erupt the oil film and to disperse the oil as flecks among the sand grains. The time should be sufficiently long to assure that the sand grains are thoroughly water wet. Normally, a pulping operation of several minutes, say 5 to 10 minutes is sufficient. It has been generally experienced in other oil extraction processes that long periods of pulping of several hours duration do not affect the yield one way or another.

With the system shown in the accompanying drawing, it is possible simultaneously to recover a bitumen or crude oil from a bituminous sand and to separate it into an asphaltene-free and an asphaltene-rich fraction. A typical crude oil that may be separated with the process has a composition comprising 24.5% by weight of saturated hydrocarbons, 24.4% (wt.) aromatic hydrocarbons, 32.2% (wt.) resins, and 18.9% (wt.) asphaltene in the use of an isopentane extraction. The oil has a pour point of 75° F., an A. P. I. gravity of 6.1° and may constitute up to 20% by weight of the tar sand. The foregoing compositions are only representative and tar oils of widely varying compositions may be processed.

Raw tar sand is placed in a feed hoper 10 which is disposed above and empties through a line 12 into a rotary type pulper 14. The pulper is a cylindrical drum having internal lifts and is provided with means for injecting steam and water to its interior. It is sometimes advantageous to inject steam along with the hot water entering through a line 15 to lower the viscosity of the oil. It is possible to use unheated water in the pulper but this is not generally done as it becomes more difficult to disrupt the oil structure of the bituminous sand. It is preferred to introduce only that heat required to erupt effectively the oil film as additional heat raises the temperature of operation of the extraction zone which is undesirable when a very volatile solvent, such as propane, is used. However, if the light ends of the crude oil are used as solvent, high pressure is not a problem because

of their low vapor pressures. The aqueous pulp leaves the pulper from its far end through a line 16 which opens into the upper end of an inclined and enclosed screw conveyor 18. The conveyor slants downwardly from the line 16 to the place where it opens into a cylindrical, vertical extraction vessel 20. It may be desirable to provide a fan 21 at the lower end of the screw conveyor for breaking up the extruded aqueous pulp and dispersing it over the cross section of the extraction zone.

The tower is supplied with a plurality of spaced conventional baffles 23 below the place of entry of the screw conveyor. Hydrocarbon solvent enters the extraction zone of the tower 20 through a line 24 which opens into the bottom of the zone. At the lower end of the extraction zone proper of the tower 20 there is a downwardly slanting baffle 25 which covers approximately two-thirds of the tower's cross section. This baffle serves to direct the cascading sand to one side of the tower. A weir 26 is disposed in the tower adjacent a portion of the tower wall and underneath the protecting baffle 25. The solvent flows upwardly through the extraction zone, contacting the downwardly descending aqueous pulp and during this countercurrent passage, the crude oil is solvent extracted to form a deasphalted oil and solvent phase and an asphaltene phase diluted with a much lesser portion of the solvent. The gravitating water wet sand particles tend to maintain the contacting mass in a somewhat turbulent state and it is believed that this serves to avoid possible plugging of the contacting zone with asphalt. As mentioned before, since the sand particles are water-wet they tend to entrain a minimum of the solvent and oil with the result the separation is more complete. Furthermore, if there should by chance be any entrained hydrocarbon on the sand, it will generally be dislodged as it passes through a water layer 28 which forms in the conical bottom of the tower. The sand collects in the bottom portion of this layer. The sand and water are removed through a suitable rotary star valve 29 in a line 30 to a flume 32. The flume is provided with a flushing water from a line 33 which moves the sand to a disposal pond.

A deasphalted oil solvent layer 35 forms in the tower above the extraction zone proper. This deasphalted oil enriched layer is removed from the tower through a line 37 to a conventional stripper where the solvent is separated from the oil and returned after cooling through the previously mentioned line 24 to the bottom of the extraction zone. An asphaltene enriched layer 39 forms in the tower immediately above the water layer 28 and below the place of introduction of the hydrocarbon solvent. The asphaltene layer is withdrawn from the tower through a line 41 opening into the bottom of a compartment 42 which is formed in the lower part of the tower between a portion of the tower wall and the previously mentioned weir 26.

The asphaltene layer spills over the top edge of the weir into the compartment 42 and collects in the bottom of that compartment, displacing any of the hydrocarbon solvent that may be there. An asphaltene-water interface level controller arrangement 44 assures that the asphaltene layer is so positioned as to spill over the weir. If the interface between the two phases should drop unduly low in the tower, a float 45 following the interface actuates the controller proper which sends a signal through a line 45 to a motor 49 mechanically linked to a valve 46. The line 45 may be either an electrical circuit or a pneumatic line. The valve 46 opens and permits water to flow under pressure through a line 47 into the tower. The water continues to flow until the interface between the asphaltene phase and water has risen to the proper level at which time a second signal is relayed to the power driven valve shutting it off. Through the foregoing arrangement, the proper level of the asphaltene layer is maintained to enable its withdrawal from the tower as an intermediate layer. The maintenance of the

water-asphaltene interface at the proper level also ensures that there will always be present sufficient water to form a pumpable sand water slurry out of the bottom of the tower and in addition, the maintenance of the water layer at an adequate depth provides for the deentrainment of any hydrocarbon material that may come down with the fine sand. Normally, however, entrainment will not occur as the surfaces of the sand grains will be water-wet which will forestall their wetting by the hydrocarbon solvent.

The extraction tower is provided with a second interface level controller arrangement 48 whose purpose is to maintain a reservoir of the asphaltene in the compartment 42. It will be appreciated that if all of the asphaltene-rich layer should be removed and there was no means for regulating the flow through the line 41, that in this instance the hydrocarbon solvent would also be withdrawn through this latter line. This possibility is prevented by the controller 48 which is provided with a float 50 adapted to follow the interface existing between the hydrocarbon solvent and the asphaltene. Here, as in the case of the other controller, if the float drops below its normal setting a signal is sent from the controller proper through a line 52 to a motor 53. The motor is mechanically linked to a valve 55 disposed in the removal line 41. The motor, where the float has dropped unduly low, moves the valve towards or to its closed position, thus, slowing up or entirely preventing the removal of the asphaltene-enriched stream. This will have the effect of raising the solvent-asphaltene interface to its proper level.

The withdrawn asphaltene-rich stream may be passed to a conventional stripper where the small amount of solvent appearing in the stream is removed and recirculated after cooling with the solvent recovered from the deasphalted oil. It may be advantageous to use the asphaltene-rich stream, without stripping, as a charge to a fluid bed coking unit. It so happens that the asphaltene-enriched stream is a fortuitously ideal charge since the light hydrocarbon solvent present acts as a dispersant for the heavier asphaltenes as they vaporize in the coker inlet nozzles. Steam is generally used for this purpose. In some operations, it may be advantageous to use the asphaltene simply as fuel. Where the asphaltene-rich layer is processed in a fluid bed coking unit, the light ends recovered therefrom may be combined with the deasphalted oils from the solvent-deasphalted oil stripper and the combined materials subjected to a desulfurization by hydrogenation. A portion of the light ends from this latter operation may be separated and used as the hydrocarbon solvent for the extraction tower. Actually, when the process is once in operation, only a small amount of the light ends need be added as make-up solvent.

We claim as our invention:

1. A process for separating crude oil from a bituminous sand in a deasphalted oil enriched layer and an asphaltene enriched layer which comprises providing an

aqueous pulp of the bituminous sand in a vertical extraction zone, introducing a liquid low molecular weight paraffinic hydrocarbon solvent into the zone at a level below the point of introduction of the aqueous bituminous sand pulp, flowing the solvent upwardly of the vertical extraction zone in countercurrent direction to the descending sand and during said countercurrent movement forming a deasphalted oil and solvent phase, an asphaltene phase diluted with a lesser portion of the solvent, a water phase, and a substantially oil-free sand, said phases and sand having increasing specific gravities in the order presented, separating the several phases and sand into layers with the asphaltene enriched layer being disposed below the place of introduction of the hydrocarbon solvent and above the water layer and sand, and with the deasphalted oil enriched layer being formed above the point of introduction of the aqueous pulp.

2. A process as described in claim 1 wherein the paraffinic hydrocarbon solvent is propane.

3. A process as described in claim 1 wherein the paraffinic solvent is made up of light ends collected from further processing of the separated crude oil.

4. A process for separating crude oil from a bituminous sand and simultaneously fractionating the crude oil into a deasphalted oil enriched portion and an asphaltene enriched portion, the improvement which comprises agitating the bituminous sand in the presence of warm water to form an aqueous pulp and during said agitation rupturing the oil structure, thereby substantially dispersing the crude oil as detached flecks among water wet sand grains, introducing the aqueous pulp to a vertical extraction zone, introducing a liquid low molecular weight hydrocarbon solvent into said zone at a point below the point of introduction of the aqueous pulp, flowing the solvent in an upwardly direction countercurrent to the descending aqueous pulp to obtain a deasphalted oil and solvent phase, an asphaltene enriched phase diluted with much less solvent than present in said other phase, water, and substantially oil free sand, separating the several phases and sand into layers, with the uppermost layer being an enriched deasphalted oil layer formed above the place of introduction of the aqueous pulp, an asphaltene enriched layer below the place of introduction of the solvent and immediately above a water layer which contains in its bottom portion the oil free sand, and removing the several phases and sand from the zone.

5. A process as described in claim 4 wherein the pH of the aqueous pulp is adjusted to the alkaline side.
